(57) **CLAIM**

The ornamental design for a ceiling light panel, as shown and described.

DESCRIPTION

FIG. 1 is a front perspective view of a ceiling light panel shown removed from any environment for clarity;

FIG. 2 is a top view thereof;

FIG. 3 is a bottom view thereof;

FIG. 4 is a rear view thereof;

FIG. 5 is a front view thereof;

FIG. 6 is a first side view thereof;

FIG. 7 is a second side view thereof; and,

FIG. 8 is a front perspective view in an environment of use in a ceiling light.

The broken lines depict portions of the ceiling light panel that form no part of the claimed design. The additional broken lines in FIG. 8 illustrating a ceiling light and ceiling light panels may be for environmental purposes only and form no part of the claimed design.

1 Claim, 5 Drawing Sheets
